Inventor:

R. Monroe Grier

UNITED STATES PATENT OFFICE.

R. MONROE GRIER, OF ST. LOUIS, MISSOURI.

GRANARY.

SPECIFICATION forming part of Letters Patent No. 293,574, dated February 12, 1884.

Application filed September 22, 1883. (No model.)

To all whom it may concern:

Be it known that I, R. MONROE GRIER, residing at the city of St. Louis and State of Missouri, have invented a new and useful 5 Granary, of which the following is a specification.

My invention relates to a grain-bin composed of a series of adjustable panels or sections, which, when properly arranged and adjusted, form a complete circle or oval-shaped bin or reservoir, encircled and held together and in place by a series of metal hoops or bands, and provided with a floor, and the whole mounted upon skids or runners; and the object of my invention is to provide an 15 outhouse adapted more especially for the storage of grain, yet useful for the shelter of fuel, tools, &c.; or the same may be used as an ice-house or smoke-house, made portable 20 by mounting upon skids or runners, as hereinbefore stated, or by separating or detaching the panels or sections, as specified. I attain these objects by the mechanism illustrated in the accompanying drawings, in which—

25 Figure 1 is a front elevation of my portable granary. Fig. 2 is a vertical section of the entire granary. Fig. 3 is a horizontal section on line 3 3 of Fig. 1. Fig. 4 is a horizontal section on line 4 4 of Fig. 1. Fig. 5 is a top 30 view of skid.

Similar letters refer to similar parts throughout the several views.

A represents the skid or foundation of my granary, made with the runners B and cross-ties C, upon which is placed the granary D, which is secured to said skid A by fastenings through the floor, or any other suitable means. If desired, the floor of granary D may be nailed or otherwise fastened directly to 40 skid A.

E represents the panels or sections of the granary D, shaped to form the necessary degrees of a circle to complete the entire circular or oval granary when properly adjusted 45 and applied in their respective places. The panels or sections E are made by properly securing closely together and parallel with each other two or more slats or staves. These may be wood, metal, paper, fabric, rubber, or other 50 suitable material.

F is the roof, which is conical-shaped, and

may be provided with a ventilator, H. The cap G may be placed upon the center pole, K, if desired; or the roof F may be finished without the cap G, and may be so adjusted and attached to the granary D as to be readily removed, if desired. 55

I I are receiving-doors, while the small doors J J may be used as discharge-doors, if desired. 60

L L L L are the separating-partitions, which, if desired, may be secured to center pole, K, by clasps M, with their projecting ends secured to the inner side of panels or sections E. The space between partitions L forms 65 the grain-bins N. The partitions L may be separately or entirely removed, thus making one bin or room of the whole granary D. The partitions L L L L and the roof F may be wood, metal, paper, fabric, rubber, or other 70 suitable material.

O O represent the ventilator-tubes or air-chutes, placed at right angles in the granary D, and may be of wood, metal, or earthen, and sufficient in number to prevent damage 75 to grain by moisture, or while in the process of "sweating." They may be placed at any point in granary D, at or between the extreme bottom or top, and may be round or semicircular, or any desired shape. The ends 80 of ventilators O may pass through panels or sections E, and may be covered with wire-gauze, perforated metal, or any other suitable material.

The panels or sections E, when properly arranged, are held firmly in their required position by means of the metallic bands or hoops which encircle the granary D, as shown in Figs. 1 and 2.

Having thus described my invention, what I 90 claim as new, and desire to secure by Letters Patent, is—

1. As a granary or other outbuilding, except water-tank, a circular or oval-shaped portable structure composed of a series of sections or 95 panels, and the whole provided with encircling outside bands or hoops, and mounted upon the foundation-skid A, substantially as shown and described.

2. A granary or outbuilding, except water- 100 tank, composed of a series of circular sectional panels provided with hoops or encircling-

bands of metal or wood, in combination with partitions, doors, and ventilators, substantially as and for the purpose specified.

3. As a granary or outbuilding, except water-tank, a circular structure provided with encircling hoops or bands, in combination with the runners B and cross-ties C.

4. In a granary, domicile, ice, fuel, or animal house, or other shelter, a circular or oval-shaped portable structure provided with hoops

or bands of metal or wood, in combination with skid A, roof F, cap G, ventilators H and O, doors I and J, center pole, K, and partitions L, all substantially as and for the purpose set forth.

R. MONROE GRIER.
